UNITED STATES PATENT OFFICE.

ALFRED W. F. GUEST, OF BROOKLYN, NEW YORK, ASSIGNOR TO MERGENTHALER LINOTYPE COMPANY, A CORPORATION OF NEW YORK

TYPE OR MATRIX.

1,126,196.

Specification of Letters Patent.

Patented Jan. 26, 1915.

Application filed March 16, 1914. Serial No. 824,857.

To all whom it may concern:

Be it known that I, ALFRED W. F. GUEST, a citizen of the United States, residing at Brooklyn, in the county of Kings and State of New York, have invented certain new and useful Improvements in Type or Matrices, of which the following is a specification, reference being had therein to the accompanying drawing.

10 My invention relates to type or matrices for typographical machines, such as linotype machines of the general organization represented in Letters Patent of the United States, No. 436,532, to O. Mergenthaler. In 15 machines of this class, the matrices are stored in a magazine, are released therefrom by the manipulation of the keyboard mechanism, are assembled in line and then presented to a mold, wherein the slug or linotype is cast. After this, the matrices are 20 distributed and restored to the magazine from which they started.

In the ordinary form of distributor, the 25 matrices are caused to pass along a grooved rail or bar until they reach the proper magazine channels, into which they drop in the manner well understood in the art. It sometimes happens that a matrix will not drop directly thereinto, but is displaced or 30 tilted to such an extent that it is caught and held, ordinarily in the channel entrance. This tilting or failure of the matrices to drop directly is caused in several ways, but chiefly by the fact that just at the moment 35 they are released from the grooves of the distributor rail, there is a tendency for them to pivot or swing about their supporting teeth, and this tendency is emphasized and increased in the case of the thicker matrices, 40 whose teeth are located at one side thereof and consequently well beyond the center of gravity.

My improvements consist specifically in 45 the formation of the matrix with a plurality of distributing combinations, preferably arranged in different vertical planes and on opposite sides of the longitudinal median line. Not only does this construction obviate the difficulty already mentioned, but in 50 addition it tends to insure the correct guiding and location of the matrices throughout the operation of the machine. It will of course be understood that the distributor bar, and the other elements engaged by the 55 matrix combinations will be suitably formed

to permit the disengagement of the matrices therefrom at the proper times, and preferably so that the several combinations will be released simultaneously at the respectively different points, thus insuring the delivery 60 of the matrices in straight lines to the magazine entrance and magazine.

I have illustrated my invention as applied to a large or thick matrix, which is provided with two distributing combinations, but obviously a larger number may be employed, and many other changes and variations may be made therein, and in the mode of application, which will still be comprised within its spirit. Similarly, the invention may be 65 adapted to type or dies, as well as to matrices. Generally speaking, I desire it to be understood that I do not limit myself to any specific form or embodiment, except in so far as such limitations are specified in the 70 claims.

Referring to the drawing: Figure 1 is a perspective view of a matrix having my invention applied thereto; Fig. 2 is a rear view of a section of a distributor bar and the improved matrices cooperating therewith; Fig. 3 is a section on the line 3—3 of Fig. 2; Fig. 4 is a section on the line 4—4 of Fig. 2; and Fig. 5 illustrates a modified form of bar.

The matrix X, which is of the large or 75 "display" variety, is formed with two unlike sets of distributing teeth or character combinations, one X¹ being located at the rear or following side in the ordinary manner, and the other or additional one X² 80 being located at a distance therefrom and beyond the median line of the matrix. Both combinations engage the grooved distributor bar A, the teeth X¹ being supported by the ridges A¹, and the teeth X² by the ridges 85 A², and consequently the matrix is held in proper perpendicular relation to the bar and its tilting tendency is thus obviated.

In order to show the adaptability of my 90 improvements to the ordinary machine, Figs. 2, 3 and 4 illustrate the ordinary or regular distributing bar A, with the normal length of distributing combination, that is to say, a length corresponding to the regular channeled magazine. In this instance, 95 the two sets of teeth X¹ and X² are located with a similar interval between them, so that they simultaneously disengage from the bar combinations A¹ and A², and the 100 matrices drop directly and vertically into 105 the magazine entrance. The drawing 110

the proper channels of the magazine entrance, as indicated by dotted lines in Fig. 2.

Fig. 5 illustrates a modification, wherein the matrix Y is of less thickness, and the 5 tooth combinations Y^1 and Y^2 are nearer each other. In this case, the distributing bar B is similarly provided with the combinations B^1 and B^2 , but the latter are cut away or formed of less extent to correspond 10 to the distance between the matrix combinations Y^1 and Y^2 .

As previously stated, I have shown my invention only in preferred form and by way of example, and in a special form of 15 application, but obviously many modifications and alterations therein, and in its mode of adaptation, will suggest themselves to those skilled in the art, without departure from its scope.

20 Having thus described my invention, its construction and mode of operation, what I claim and desire to secure by Letters Patent of the United States, is as follows:

1. A type or matrix having at one end 25 two character-distributing combinations arranged in different vertical planes setwise thereof.

2. A type or matrix having two unlike 30 character-distributing combinations arranged in different vertical planes setwise thereof.

3. A type or matrix having two distributing 35 combinations arranged in different vertical planes setwise thereof.

4. A type or matrix having two distributing 40 combinations arranged setwise on opposite sides of its longitudinal median line.

5. A type or matrix having separate and distinct means to support it at both its 45 front and rear sides during distribution.

6. A type or matrix formed with several sets of sustaining teeth arranged in different vertical planes setwise thereof.

7. A type or matrix formed with two sets of sustaining teeth arranged setwise on opposite sides of its longitudinal median line. 45

8. A type or matrix adapted to traverse a distributor bar and to be sustained by separate and distinct means at its opposite sides and at different points in the length 50 of the bar during its movement therealong.

9. A type or matrix formed with separate and distinct means to engage a distributor bar simultaneously at different points in the length thereof. 55

10. A type or matrix formed with separate and distinct means to engage a distributor bar at different points in its length and to be released therefrom simultaneously at its different points of engagement. 60

11. A type or matrix having a plurality of distributing combinations to coöperate simultaneously with two or more combinations arranged at different points in the length of a distributor. 65

12. A type or matrix formed with a plurality of tooth combinations to coöperate with two or more tooth combinations arranged at different points in the length of a distributor bar. 70

13. A type or matrix adapted to traverse a distributor and to be sustained by separate and distinct means at different points in the length thereof during its travel.

In testimony whereof I have affixed my 75 signature in presence of two witnesses.

ALFRED W. F. GUEST.
